CARPET STRETCHER

Harry E. Cathcard, Independence, Mo.

Application March 14, 1932. Serial No. 598,730

7 Claims. (Cl. 254—59)

This invention relates to carpet laying apparatus and specifically to means for stretching a carpet or similar floor covering after it is secured to the floor by tacks or fastening elements.

5 The primary object of the instant invention is to provide a carpet stretcher having as a part thereof, a brace that might be utilized in interconnecting one wall of the room being carpeted and an extensible assembly whereby the entire 10 width or length of floor covering might be subjected to a stretching action immediately prior to its being fastened in place.

A yet further object of this invention is the provision of carpet stretching assembly having a 15 normally stationary body and a carpet-engaging head carried by the body and movable relative thereto, said body and head being uniquely interconnected for relative displacement by structure embodying the features of this invention.

20 A still further object of the invention is the contemplation of an extensible carpet laying and stretching assembly, wherein is incorporated a novel head having spurs or like members disposed in particular arrangement for the purpose and 25 function as hereinafter set down.

A number of minor objects, including structural features and method of using the device will appear during the course of the following specification, which refers to the accompanying drawing, wherein:

Figure 1 is a diagrammatical sectional view through a room being carpeted through the use of a stretcher embodying the features of this invention.

35 Fig. 2 is a top plan view on an enlarged scale of only the extensible carpet engaging assembly.

Fig. 3 is a longitudinal, vertical section through the assembly illustrated in Fig. 2.

Fig. 4 is an inverted plan view of the same assembly shown in Fig. 2, and,

Fig. 5 is a front, edge elevation of the carpet engaging head.

In describing the carpet stretcher, only the preferred form will be made clear by reference to parts making up the same as it is shown in the drawing and, while the carpet stretcher might be used in laying floor covering practically any place, the same is here shown in connection with the placing of a carpet or floor covering 6 upon floor 8 of an ordinary room 10, having opposite, parallel and vertical side walls 12, near the base of which are installed baseboards 14 in the ordinary fashion. It is always desirable to secure a point of purchase beyond the edge of carpet 6, whereby the same may be stretched without setting up

forces which exert an action against each other. To do this, the extensible carpet engaging assembly 16 is placed near the edge of carpet 6 that has not been tacked in place and a brace consisting of a plurality of telescoping parts 18 adjusted to reach from wall 12 to assembly 16, as shown in Fig. 1.

Adjustment on the part of telescoping parts 18 might be secured through the provision of a plurality of holes 20 and cross pins 22 which pass through registering holes 20 of telescoped members 18 after the distance between wall 12 and assembly 16 has been determined. One end of this brace should be provided with a foot 24 of resilient or padded material which will preclude marring at 65 its point of pressure. This brace made up of sections 18 must lie along above carpet 6 in a plane parallel thereto and must be straight and rigid before it fulfills the prime reason for its use. After abutting pad 24 against baseboard 14 of wall 70 12, the telescoping member 18 of the brace at the other end is secured to assembly 16 by bolts or analogous means 26. Thus body 28 of structure 75 16 is held against movement toward wall 12, against which the brace is now abutting.

Obviously, carpet 6 has been previously tacked along wall 12, as shown at the left in Fig. 1 and the next step in laying the same is to stretch carpet 6 toward wall 12 as at the right in Fig. 1 through the use of structure 16 which is secured 80 against movement toward left wall 12 by the brace just described. Assembly 16 is extensible to the degree that it includes a carpet-engaging head 30 that is associated with body 28 by a pair of guides having a tube 32 and a telescoping rod 34 rigidly affixed to body 28 and head 30 respectively. Attachment may be effected through any ordinary means such as fixtures and bolts 36 and 38 respectively, and it is to be seen that such guides permit only rectilinear reciprocation between body 28 and head 30 respectively.

A force of an appreciable degree must be used in properly stretching carpet 6, and such force may be imparted to head 30 by manually manipulating the parts provided for that purpose 100 through the medium of a handle 40 having one end thereof secured as at 42 to pinion 44. This pinion 44 stands vertically between a pair of spaced apart, vertical, substantially parallel walls 46 having an opening 48 formed therethrough to permit interconnecting pinion and handle 44 and 40 respectively. Pinion 44 floatingly rests between walls 46 and is free to rotate when handle 40 is brought into play. A stationary rack 50 is rigidly secured between walls 110

46 along the top thereof so that the teeth of rack 50 extend downwardly toward the base of body 28. Thus rack 50 becomes a spacing element for walls 46 along the tops thereof and since handle 40 is bifurcated to straddle walls 46, the assembly at this particular point should be as narrow as possible. Such feature is shown clearly in Fig. 2.

Between walls 46 and at the bottom thereof is positioned a movable rack 52, which is housed between walls 46 and projects therefrom to engage head 30 as at 54 and it is between racks 50 and 52 that pinion 44 may be actuated when the teeth of said elements are in mesh.

15 Since rack 50 is stationary and rack 52 is movable, rack 50 becomes a fulcrum about which pinion 44 moves as it forces movable rack 52 along its path of travel. Small toothed guide rollers 56 may be pivotally secured between walls 20 46 in engagement with rack 52 to lend stability to assembly 16. They are free to rotate and do so as rack 52 reciprocates to move head 30 toward and from body 28. Enormous leverage is possible through an assembly of this character and when 25 carpet 6 has been stretched the desired amount, it is always desirable to hold the position attained until the carpet is tacked in place. To do this, the assembly here described should include a pawl 58 that is bifurcated to present a 30 pair of opposed walls 60 which embrace walls 46 and are pivotally engaged thereby through the medium of a bolt or like element 62. Pawl 58 is pivotally mounted as shown in Fig. 3 so that it has a jaw 64 in the path of travel of the teeth 35 of rack 52. A grip 66 is formed by pawl 58 that extends outwardly to contribute its weight to the rest of pawl 58 so that the action of gravity will always urge jaw 64 into position between the teeth of rack 52.

40 Grip 66 not only performs the function just mentioned, but presents means whereby the entire assembly may be grasped when moving the same from one position to another. When so grasping the assembly, pawl 58 is immediately 45 moved to an inoperative position and rack 52, with head 30, may be quickly moved back to a point of beginning so that the carpet stretching operation is greatly facilitated. The position of handle 40 and head 30 in both the carpet stretching and nonstretching position is shown in 50 Fig. 1.

Head 30 of this assembly 16 is likewise especially formed in that it has a large number of spurs 68, all projecting beyond the face of head 30 and angled as shown in Fig. 3, whereby to more securely engage carpet 6.

It has been found in practice that the creation of a zone of greater gripping ability adjacent the ends of head 30 is extremely desirable. Such zones are set up by massing spurs 68 as shown in 60 Fig. 4 so that there will be no excessive strain of the carpet at edges of head 30. The creation of these zones will move a length of carpet toward wall 12 and maintain its edge in a position parallel thereto. The depth to which spurs 68 enter carpet 6 is sometimes altered and such expedient is permitted through the use of the plate 70 that is adjustably associated with the front edge of head 30 by slots and bolts 72 and 74 respectively. 70 A flange 76 should be formed along the edge of plate 70 to create a smooth supporting face and to present an area great enough to preclude sinking of the entire head structure into the nap of carpet 6.

Operation of this carpet stretching assembly has been made clear during the course of specification, and while some specific features have been set down, it is desirous to be limited in the enjoyment of this invention only by the spirit thereof and the scope of the appended claims. 80

Having thus described the invention, what is claimed as new and desired to be secured by Letters Patent is:

1. A carpet stretcher comprising an extensible assembly having a normally stationary body; a head movable relative thereto; means for moving said head including a rack on the body, a rack on the head, and a pinion in mesh with both of said racks and a pair of guides connecting the said body and head comprising a tube mounted on said body and a rod in telescoping engagement with said tube carried by said head. 85

2. A carpet stretcher comprising an extensible assembly having a normally stationary body; a head movable relative thereto; and means for moving said head including a fixed rack on the body, a rack movable with said head, a pinion in mesh with both of said racks, and a pair of guide walls to maintain said pinion in mesh with said 95 racks.

3. A carpet stretcher comprising an extensible assembly having a normally stationary body; a head movable relative thereto; and means for moving said head including a rack on the body, a rack on the head, a pinion in mesh with both of 105 said racks, and telescoping guides associated with both the body and head.

4. A carpet stretcher comprising an extensible assembly having a normally stationary body; a head movable relative thereto; means for moving said head including a fixed rack on the body, a rack movable with said head, a pinion in mesh with both of said racks; a gravity actuated pawl for holding said movable rack in position as the 110 same is moved by the rotation of said pinion; and an idler guide gear in mesh with said movable rack, said pawl being pivotally mounted on the axis of said idler gear.

5. A carpet stretcher comprising an extensible 120 assembly having a normally stationary body; a head movable relative thereto; means for moving said head comprising a fixed rack on the body, a rack movable with said head, and a pinion in mesh with both of said racks; a telescoping guide 125 on each side of said movable rack; and a pawl associated with said movable rack to releasably hold the same against movement.

6. A carpet stretcher comprising a normally 130 stationary body; a head movable relative thereto; telescoping, tubular guides interconnecting said body and head whereby to permit rectilinear, reciprocating movement toward and from each other; a pair of upstanding substantially parallel, spaced apart walls mounted on said body; a 135 rack along the upper portion of said walls, therebetween and secured thereto; a rack movable along between said walls at the lower portion thereof; a pinion between said walls and in mesh with said racks; and means mounted on the walls 140 for releasably holding the movable rack against movement.

7. In a carpet stretcher, a head; and a plurality of carpet piercing spurs extending below the face of said head, said spurs being arranged 145 appreciably closer together adjacent the ends of said head whereby to create spaced apart zones of greater gripping ability.

HARRY E. CATHCARD.
